UNITED STATES PATENT OFFICE.

HARPER M. HUPMAN, OF DETROIT, MICHIGAN, ASSIGNOR TO MICHIGAN OPTICAL COMPANY, OF DETROIT, MICHIGAN, A CORPORATION OF MICHIGAN.

RIM-CLAMP-ATTACHING DEVICE.

1,387,491.

Specification of Letters Patent. Patented Aug. 16, 1921.

Application filed March 21, 1921. Serial No. 454,250.

To all whom it may concern:

Be it known that I, HARPER M. HUPMAN, a citizen of the United States, and residing at Detroit, in the county of Wayne and State 5 of Michigan, have invented a new and Improved Rim-Clamp-Attaching Device, of which the following is a specification.

This invention relates to means for removing the still attached portion of broken lens 10 rims of eye glasses and spectacles from the bridge and temple clamps and for securing these clamps to new lens rims, and it consists in a base provided with a die to hold the bridge or temple end and the rim, a vertically 15 movable head and bending plates secured thereto adapted to bend the clamps of said attachments toward each other, and a central plate movable between the two other bending plates for forming a channel between the ends of these clamps so as to form 20 a groove to receive the edge of the lens. It further consists in a pedestal for guiding this vertically movable head and a lever for moving it up and down. It also consists in 25 a rotatable shaft adapted to be mounted in said pedestal and a curved blade mounted on the shaft and adapted to spread the clamps of the attachments and remove the remnants of the broken lens rims therefrom.

30 In the accompanying drawings Figure 1 is a side elevation and Fig. 2 a front elevation of this improved machine. Fig. 3 is a central vertical section of the bending head. Fig. 4 is a central vertical section of a die 35 with the work in position and the bending plates just above the work. Fig. 5 is a similar section with the bending plates after they have completed the first portion of their operation. Fig. 6 is a similar view after 40 the bending plates have completed the second portion of their operation. Fig. 7 is a side elevation of this machine when employed to remove broken parts of lens rims from the clamps. Fig. 8 is a section on the line 8—8 45 of Fig. 7. Fig. 9 is a longitudinal section on the line 9—9 of Fig. 8. Fig. 10 is a plan of a die.

Similar reference characters refer to like parts throughout the several views.

50 The rims of eye glasses or spectacles are often made of fragile material, such as tortoise shell and celluloid, and when they become broken it is difficult to remove these parts from the clamps to which the temples

and bridges are connected and it is difficult 55 to replace the rims by means of hand tools. The present device is a cheap and efficient mechanism for performing this work.

In Figs. 1 to 6 inclusive, I have shown a base 1 and a pedestal 2 having a pivot pin 3 in its upper end for the lever 4. This lever is formed with a small slot to receive the pin 5 in the upper end of the plunger 6. This pin 5 is preferably screw threaded so it may be readily removed that these parts may be 60 connected. At the front of the pedestal 2 are guides 7 for the vertical movable head 8 which is in the form of a rectangular bar, the head being held in position by means of a plate 9 secured to the guides 7 by means 65 of the screws 11 and 12, the latter preferably being formed with a wing head and the plate 9 being formed with a notch 12 so that it may swing away to the position shown in Fig. 8. 75

This head 8 is formed with a central bore 14 in which is mounted a spring 15 and the reduced lower end 16 of the plunger 6. The part 16 is formed with a notch 17 which receives the pin 18. The front of the head 8 80 is grooved to receive a plate 19 attached to the plunger 6 by means of the pin 20. The lower end of the plate 19 extends between the two cross plates 22 which are secured to the head 8 by means of screws 23. The 85 plate 19 is freely slideable between these plates 22, the latter being held apart by means of the spacers 24 shown in Fig. 1. As shown in Figs. 1 to 6 inclusive, the transverse plates 22 have their lower edges sloping up inwardly and the plate 19 has its lower edges beveled in both directions and the lower ends of these three plates are curved to substantially fit the eye glass 90 rim A. 95

Mounted in a groove in the base is a die 25 which is preferably formed with two circular notches 26 and 27, one having a lateral extension 28 to permit the insertion of a bridge piece and the other having a vertical extension 29 to receive the arm 30 of a temple end. When the parts are as shown in Figs. 2 and 4, the small clamps 32 of the temple end extend upwardly and the rim A is placed substantially vertically into this 100 groove 27 and between the clamps 32. The lever 4 is then depressed, bringing the transverse plates 22 down against the clamps 32 105

and causing them to bend in toward each other as shown in Fig. 5. This is possible because of the stiffness of the spring 15 which forces down the head 8 and the transverse plates 22. But when the plates 22 can no longer move downwardly, having reached the limit shown in Fig. 5, continued movement of the lever 4 will force down the plunger 6 against the pressure of the spring 15 and thereby cause the plate 19 to move down relative to the transverse plates 22 as shown in Fig. 6, causing the upper edges and now the inner edges of the clamps 32 to be crimped down together, as shown in Fig. 6, which not only rigidly secures the attachment to the rim, but also forms a continuation of the groove which is formed on the interior of the rim for the lenses.

It will be understood that where the lens rims A vary greatly in diameter, that additional dies must be substituted and other plates 19 and 22 with proper curvature mounted on the plunger 6 and head 8 but ordinarily a considerable range of variations in diameter will be taken care of by the same set of plates and dies.

When it is desired to remove a broken piece of rim from bridge or end, the attachment with the fragment of rim is inserted in the die in the same manner as shown in Fig. 6; but the handle is raised, the screw 12 turned back to permit the plate 9 to be swung to the left and the head 8 is swung out from between the guides 7 to the position shown in Fig. 7. A shaft 35 has a reduced end 36 which is adapted to journal in a hole 37 in the pedestal 2, and on this shaft is secured a hook 38, such as shown in Fig. 8 having a sharp point 39 which is adapted to be swung against the broken end B between the clamps 32 of the attachment. The shaft may be freely turned by means of the handle 40 and the pointed end 39 when forced through between the clamps 32 not only forces out the broken piece B of the rim, but it also separates these clamps until they are in the position shown in Fig. 4. The shaft is then removed, the head 8 swung back into position, the plate 9 secured over this head, and a new rim A may then be placed in the groove 27 and secured by means of the plates 19 and 22, as before described.

I prefer to form the dies 25 with indentations 41 indicated in Fig. 10 in their edges to receive the end of the screw 42, whereby the die is held in pre-determined position. No particular means need be employed to secure the bridges or ends in position in the grooves in the die, the extensions of these parts in the notches 28 and 29 being sufficient to hold them in position. The details, sizes and proportions of the various parts of this machine may all be changed without departing from the spirit of my invention as set forth in the following claims.

I claim:—

1. In combination, a base, a die mounted thereon having a groove to receive a rim for an eye glass lens, a vertically movable head, a pair of beveled plates at the lower end of the head adapted to engage the clamps of an attachment for the rim, and bend the clamps toward each other, and a plate mounted on the head and slidable between the plates of said pair to bend the inner edges of the clamps to constitute a groove. 75

2. In combination, a base, a die mounted thereon and having a groove to receive a lens rim and an attachment therefor including side clamps, a vertically movable head, having a longitudinal bore, a spring mounted therein, a plunger mounted in said bore in engagement with the spring, a pair of spaced beveled plates at the lower end of the head adapted to engage the clamps of an attachment and bend them around the rim, a plate mounted on said plunger and slidable between the plates on the head to bend the inner edges of the clamps to constitute a groove, and means to force the plunger toward the die. 90

3. In combination, a die having a groove to receive a lens rim and an attachment therefor including side clamps, of a pair of plates to bend the clamps of the attachment around the rim, and a third plate slidable between the first two to produce a groove between the edges of the clamps. 95

4. In combination, a support for the rims of eye glasses and the attachments therefor including side clamps, of a pair of spaced plates for bending the side clamps of said attachment around the rims, and means for bending the edges of the clamps inward. 100

5. In combination, a support for the rims of eye glasses and the attachments therefor including side clamps, of a pair of spaced plates for bending the side clamps of said attachment around the rims, and means for bending the edges of the clamps inward consisting of a positively operated wedge plate whose operative edge has substantially the same cross section as the edge of the lenses of the eye glasses to be inserted in said rims. 110 115

6. In combination, a base, a die mounted thereon having a groove to receive the rim for an eye glass lens, a vertically movable head, a pair of beveled plates resiliently connected to the head and extending downwardly therefrom and adapted to engage the outer sides of the clamps of an attachment for the rim and bend the clamps toward each other, and a plate rigidly mounted on the head and slidable between the plates of said pair to bend the inner edges of the clamps inwardly to constitute a groove after the first named plates have completed their work and stopped moving. 120 125
